(57) **CLAIM**

I claim the ornamental design for a personal storage system, as shown and described.

DESCRIPTION

FIG. 1 is a perspective view of the personal storage system showing our new design.

FIG. 2 is a top view thereof.

FIG. 3 is a bottom view thereof.

FIG. 4 is a side view thereof, the opposing side being a mirror image thereof.

FIG. 5 is a front view thereof.

FIG. 6 is a rear view thereof.

FIG. 7 is a first perspective view thereof, shown in an open condition of use.

FIG. 8 is a bottom perspective view thereof.

FIG. 9 is a top view thereof.

FIG. 10 is a bottom view thereof.

FIG. 11 is a side view thereof, the opposing side being a mirror image thereof.

FIG. 12 is a front view thereof; and,

FIG. 13 is a rear view thereof.
